COMBINED PANTY GIRDLE AND WAIST CINCHER

Lee R. Smith, Montclair, N.J., assignor to Lido Foundations International, Inc., New York, N.Y.

Filed Jan. 2, 1975, Ser. No. 537,926

Term of patent 14 years

Int. Cl. D2—01

U.S. Cl. D2—4

FIG. 1

FIG. 3

FIG. 1 is a front elevational of a combined panty girdle and waist cincher showing my new design;

FIG. 2 is a rear elevational view; and

FIG. 3 is a front and partial left side perspective view.

I claim:

The ornamental design for a combined panty girdle and waist cincher, as shown.
